[57] ABSTRACT

The closure is made to require a certain manipulation to remove the closure from a container and, hopefully, this manipulation is beyond the skill of a child. The closure comprises an inner metal cap and an outer plastic cap. A one-way engagement means between the metal cap and plastic cap permits the closure to be placed upon the bottle, but prevents removal of the closure from the container. An interlock structure requiring the downward movement of the plastic cap relative to the metal cap for engagement is used for removal of the closure from the container. The resiliency of the dome of the plastic cap keeps the interlock structure normally out of engagement.

CHILD-SAFE CLOSURE

BACKGROUND OF THE INVENTION

This application is a continuation of Ser. No. 812,004 filed Apr. 1, 1969, now abandoned.

1. Field of the Invention

The invention relates to a safety closure and more particularly to a closure which can be applied and removed easily from a container by one having knowledge of its operation, but is relatively safe so far as removal by children is concerned.

2. Description of the Prior Art

A similar type of child-safe disclosure is shown in U.S. Pat. No. 3,055,524. This structure uses an inner or primary closure which is retained within an outer shell, and the retention means is such that the two closures are maintained in axial alignment with one another, but can rotate with respect to one another in at least one direction when torque is applied to the outer shell. The respective diameters of the inner closure and the outer shell are such that the inner closure is received within the outer shell with sufficient clearance that they can rotate freely with respect to one another with insufficient frictional drive for the outer shell to rotate the inner closure when torque is applied. When the two members are in their assembled state, the inside of the top portion of the outer shell and the exterior of the top portion of the inner closure are in juxtaposition and rotate freely about the same central axis. Means are provided to hold the top of the outer shell away from the top of the inner closure under normal circumstances. The force by which these are held apart is such that it can be overcome by the application of downward pressure to bring them into interlocking engagement for rotation with one another. Upon the application of downward pressure to the outer shell, engagement means positioned on the bottom surface of the top of the outer shell mesh with the engagement means on the top surface of the inner closure. When these engagement means are in mesh, rotation of the outer shell rotates the inner closure for removal from the container.

The advantage of the closure disclosed herein is that it provides for one positive one-way engagement means between the inner and outer caps for forcing the closure onto the container, but that means is not capable of removing the closure from the container. A second structure, requiring a certain manipulation, is necessary for the removal of the closure from the container.

SUMMARY OF THE INVENTION

The closure herein is comprised of two parts; namely, a base metal cap and a plastic outer cap. The metal cap has raised projections on its dome, and these projections interlock positively with projections on the inside of the dome of the outer plastic cap. When screwing the closure onto a container, the projections engage and the outer cap drives the base cap. On unscrewing, the projections slide over one another to prevent the outer cap from moving the base cap. This structure provides the one-way engagement means. The base metal cap has a series of interruptions in the bead at the lower end of its skirt. The outer plastic cap has a series of vertical bars on its inside wall. The two caps are held normally apart by a boss on the inside dome of the outer cap. The closure is removed by pressing down the outer cap to interlock the vertical wall ribs of the outer cap with the interruptions in the bead of the base metal cap. The boss on the inside of the dome of the plastic cap acts as a fulcrum point, and the resiliency of the material for the outer cap permits the movement of the outer cap downwardly relative to the base cap.

BRIEF DESCRIPTION OF THE DRAWING

FIG. 1 is a top view of the closure;

FIG. 2 is a cross-sectional view of the closure showing the dome interlock structure;

FIG. 3 is a cross-sectional view of the cap in its application position; and

FIG. 4 is a cross-sectional view of the cap in its removal position.

DESCRIPTION OF THE PREFERRED EMBODIMENT

The closure 2 is composed of a base metal cap 4 and a plastic outer cap 6. The base cap 4 has internal threads 7 which are used to fasten this cap to a container. In the dome 8 of the metal cap there is provided ramp-type louvers or lugs 10 as best seen in FIG. 2. These louvers 10 are merely raised portions stamped into the dome of the metal cap.

The plastic outer cap 6 has ramp-type lugs 12, as best seen in FIG. 2, which coact with the louvers 10 to form a one-way engagement means. As best seen in FIG. 2, rotation of the outer cap to the left will cause the flat surface 14 of lug 12 to engage the flat surface 16 of the louver 10 and cause corresponding rotation to the left of the metal cap. Rotation of this type will be used to apply the closure to a container; and, therefore, it can readily be seen that rotation of the outer cap causes rotation of the base cap to cause the threads 7 of the base cap to engage the threads of a container. It should be noted that rotation of the outer cap to the right will cause the inclined surface 18 of lug 12 to slide over the inclined surface 20 of the louver 10. This rotation to the right is the rotation that would be used to remove the closure from the container. Therefore, it can be seen that rotation of the outer cap in an attempt to remove the closure from the container will not permit the outer cap to rotate the inner cap through the use of the louver 10 and lugs 12. FIG. 3 is a representation of the relative position of the outer cap and base cap when the interlock structure is being used to fasten the closure to a container.

The base cap 4 has a bead structure 22 around the lower edge of its skirt. A series of interruptions or small slots 23 is placed in the bead structure. Four or more interruptions are desirable. The outer cap 2 is provided with a plurality of vertical ribs 24 which are spaced apart around the inside of the skirt of the outer cap the same distance apart that the interruptions are spaced around the bead 22 of the base cap 4. Engagement of the vertical ribs in the interruptions will provide a positive drive between the outer cap and the base cap.

The outer cap is provided with a boss 26 which rests upon the upper center portion of the dome of the metal base cap. As best seen in FIG. 3, the outer cap and the inner cap are spaced from each other by the boss 26 with only a portion of the flat surfaces 14 and 16 being in engagement to permit the application of the closure to a container. Referring to FIG. 4, it will be seen that the application of a downward pressure to the outer cap will permit downward movement of the ribs 24 into the interruptions in the bead 22. The positive engagement between the outer and inner cap will now permit the removal of the closure from a container. The boss 26 acts as a fulcrum point about which the resilient dome of the outer cap can bend to permit the downward movement of the vertical ribs into the interruptions. As soon as the downward pressure is released on the outer cap, the resiliency of the dome of the outer cap will move the skirt of the outer cap upwardly disengaging the contact between the vertical ribs and the interruptions on the metal bead of the base cap.

What is claimed is:

1. A closure for fastening to containers comprising: an outer cap having a skirt portion, an inner base having a skirt portion cap, said outer cap overlying said inner cap and being coaxial therewith, container fastening means on the inside skirt portion of the inner cap, ramp-type lugs on the upper surface of the dome of the inner cap and on the inner surface of the dome of the outer cap, said ramp-type lugs constituting a one-way engagement means which will permit the lugs to engage when the outer cap is being rotated in a direction to apply the closure to a container so that rotation of the outer cap in the application direction causes rotation of the inner cap, but rotation of the outer cap in a removal direction to remove the closure from a container will result in the ramp-type lugs of the one-way engagement means sliding over each other so that

the rotation of the outer cap does not rotate the inner cap, said inner cap being provided with a bead structure at the lower end of its skirt, said bead structure having a series of interruptions, said outer cap having a plurality of vertical ribs on the interior of its skirt portion, said vertical ribs and bead interruptions normally being out of engagement, a boss in the dome of the outer cap resting against the dome of the inner cap and holding the ribs and interruptions out of engagement, the dome of the outer cap being resilient so that downward movement of the outer cap relative to the inner cap will permit engagement of the ribs and interruptions while removal of the downward force lets the resiliency of the dome of the outer cap provide disengagement of the vertical ribs and interruptions in the bead whereby removal of the closure can be accomplished only when the ribs engage the interruptions.

2. A closure for fastening to containers comprising: an outer cap having a skirt portion, an inner base cap having a skirt portion, said outer cap overlying said inner cap and being coaxial therewith, container fastening means on the inside skirt portion of the inner cap, ramp-type lugs on the upper surface of the dome of the inner cap and on the inner surface of the dome of the outer cap, said ramp-type lugs constituting a one-way engagement means which will permit the lugs to en-

gage when the outer cap is being rotated in a direction to apply the closure to a container so that rotation of the outer cap in the application direction causes rotation of the inner cap, but rotation of the outer cap in a removal direction to remove the closure from a container will result in the ramp-type lugs of the one-way engagement means sliding over each other so that the rotation of the outer cap does not rotate the inner cap, said inner cap being provided with an outwardly projecting structure extending around its skirt and having a series of interruptions, said outer cap having a plurality of vertical ribs on the interior of its skirt portion, said vertical ribs and outwardly projecting structure normally being out of engagement, a boss in the dome of one of said caps resting against the dome of the other cap and holding the ribs and interruptions out of engagement, the dome of one of said caps being resilient so that downward movement of the outer cap relative to the inner cap will permit engagement of the ribs and outwardly projecting structure while removal of the downward force lets the resiliency of the resilient dome provide disengagement of the vertical ribs and outwardly projecting structure whereby removal of the closure can be accomplished only when the ribs engage the structure.
